UNITED STATES PATENT OFFICE.

FRANK S. CRAVENS, OF OLIVE HILL, KENTUCKY.

AIR-BRAKE APPARATUS.

1,137,701.

Specification of Letters Patent. Patented Apr. 27, 1915.

Application filed November 11, 1914. Serial No. 871,576.

To all whom it may concern:

Be it known that I, FRANK S. CRAVENS, a citizen of the United States, residing at Olive Hill, in the county of Carter and State 5 of Kentucky, have invented new and useful Improvements in Air-Brake Apparatus, of which the following is a specification.

My present invention relates to improvements in air brake apparatus on railway 10 trains, it being an improvement upon that shown and described in my prior patent, No. 988,864, granted April 4, 1911, and the primary object of the invention is to provide simple and improved means whereby all the 15 angle cocks throughout the length of a train shall be opened automatically and maintained in open position during normal conditions in operations of the train when air at normal pressure is admitted to or present 20 in the train pipe, thereby insuring the correct action of the brakes on all cars comprising the train and preventing closing of any one or more of the angle cocks by accident or by unauthorized persons, means, however, 25 being provided whereby a trainman may close any one of the cocks when it is necessary to do so in uncoupling a car or for any other reason.

To these and other ends, the invention 30 consists in certain improvements, and combinations and arrangements of parts, all as will be hereinafter more fully described, the novel features being pointed out particularly in the claims at the end of the specification.

35 In the accompanying drawing:—Figure 1 is a side elevation, partly in section, of an angle cock for air brake apparatus constructed in accordance with the present invention; Fig. 2 is a top plan view, partly in 40 section, and with parts removed, showing the device illustrated in Fig. 1; Fig. 3 represents a section on the line 3—3 of Fig. 1; Fig. 4 represents a horizontal section through the device showing the arrangement 45 of air passages; Fig. 5 represents an enlarged detail view showing a portion of the air cylinder and one of the air passages leading thereto; Fig. 6 represents a section on the line 6—6 of Fig. 5.

50 Similar parts are designated by the same reference characters in the several views.

In the present instance I have shown the invention applied to the ordinary or standard angle cock, modified slightly, however, 55 to adapt it for use in connection with the present invention. This cock consists generally of a casing 1, one end 2 of which is

threaded to receive the brake or train pipe which extends beneath the car while the opposite end 3 of the casing is inclined downwardly and is threaded or otherwise adapted to receive the usual flexible coupling hose by means of which the brake or train pipe is rendered continuous throughout the length of the train. The plug 4 of the cock is rotatably fitted as usual in the casing, the interior of the casing being preferably provided with a bushing 5 in which the plug is rotatable. The plug is formed with a passage 6 and turning of the plug presents this 70 passage either in line with the passageway through the cock, the cock being then in open position, or in a position transverse to the passageway through the casing when the cock is closed.

According to the present invention, air-operated means is provided for automatically opening the cock when air at normal pressure is admitted to the train pipe and for holding the cock in open position while 80 the train pipe is charged with air. In the present instance the air-operated means comprises a cylinder 7 which may be conveniently cast as a part of the casing 1, this cylinder having a piston 8 fitted to reciprocate therein, and the end of the cylinder is closed by a head 9. A piston rod 10 is connected to the piston and extends through one end of the cylinder 7 into a housing 11, the latter having a longitudinal recess or groove 90 12 which provides a guide for the piston rod 10. The piston rod is formed with gear teeth 13 whereby it may perform the function of a rack. The upper end of the plug 4 is formed with an angular portion 14, and 95 a gear or gear segment 15 is fitted upon the angular portion 14 of the plug, the gear or gear segment being located in a pocket or recess 16 which is formed in the housing 11. The housing 11 is preferably formed with an 100 open top to permit assembling of the parts and it is provided with a lid or cover plate 17 which is adapted to be tightly fitted thereon, the housing, together with its lid or cover plate, providing a tight closure to 105 protect the rack-shaped piston rod and its operating gear or gear segment from ice or snow or other foreign matter which might interfere with its operation. The angular portion 14 of the plug extends through the lid or cover plate 17 and the usual handle 18 is fixed thereon whereby the plug may be closed by hand when necessary.

In order to prevent entrance of ice, snow

or other foreign matter into the housing through the opening of the lid through which the angular stem 14 of the plug passes, a washer 19 may be applied to the 5 squared end of the stem 14 of the plug; this washer having an aperture shaped to fit the angular portion of the plug and a circular circumference which fits closely within a circular opening 20 formed in the lid or 10 cover plate 17. This washer is interposed between the gear or gear segment 15 and the hub of the handle 18 and corresponds in thickness to the thickness of the lid or cover plate 17. An air passage 21 leads from the 15 air passageway in the casing at one side of the plug 4 and another air passage 22 leads from the passageway through the casing at the opposite side of said plug, these air passages leading to the outer end of the cylinder, and grooves 23 and 24 connect the ends 20 of these passages with the cylinder whereby air approaching the cock from either direction will flow through one or another of the air passages 21 and 22 into the cylinder and 25 will force the piston 8 outwardly, rotating the gear or gear segment 15 and consequently turning the plug 4 from its normal closed position to open position, thereby automatically opening the cock upon admission 30 of air to the train pipe. Furthermore, the presence of air under pressure in the train pipe insures the maintenance of the cock in open position as air under pressure acts upon the piston 8 to hold the cock open. 35 In order to economize in the amount of air required in opening the cock, reducing bushings or plugs 25 and 26 are preferably fitted into the air passages 21 and 22, these reducing bushings having openings just sufficient in size to admit the necessary amount 40 of air to open the cock as required.

In order to enable a trainman to close the cock when it is desired to uncouple a car or for any other reason, means is provided for 45 releasing the pressure of air behind the piston in order to permit the cock to be closed by manipulation of the handle 18. In the present instance a relief valve 27 is fitted into the cylinder head 9, this relief valve 50 being of any suitable construction such, for example, as that shown in my prior patent aforesaid, and in order to prevent unauthorized persons from tampering with the valve without detection, the air released 55 from the cylinder by the relief valve preferably passes to a whistle or other audible signal 28 which may also be of any suitable construction such, for example, as that shown in my prior patent aforesaid. 60 For the purpose of preventing leakage of air from the train or brake pipe while the pressure is acting on the piston to hold the

cock open, a disk or washer 29 of leather, rubber or other suitable packing material may be placed at the forward end of the cylinder to be compressed by the piston as the latter is forced forward to the limit of its stroke.

I claim as my invention:—

1. In air brake apparatus, the combination of a cock for the brake or train pipe having a rotatable plug, a cylinder and a piston reciprocable therein, passages connecting one end of the cylinder with the cock at opposite sides of said plug, a rack connected to reciprocate with the piston, a gear member cooperative with said rack and connected to the plug for turning the latter to open the cock by air pressure from either side of said plug, a housing inclosing the gear member and rack, and a manually operative handle connected to the plug exteriorly of the housing.

2. In air brake apparatus, the combination of a cock for the brake or train pipe having a rotatable plug, a cylinder and a piston reciprocable therein, passages connecting one end of the cylinder with the cock at opposite sides of said plug, a rack connected to reciprocate with the piston, a gear member actuated by said rack and connected to said plug, and a housing inclosing said rack and gear member.

3. In air brake apparatus, the combination of a cock for the brake or train pipe having a rotatable plug, a cylinder and a piston reciprocable therein, passages connecting one end of the cylinder with the cock at opposite sides of said plug, a rack connected to reciprocate with the piston, a gear member actuated by said rack and connected to said plug, an open-topped housing inclosing said rack and gear member, a lid fitted to and closing the top of said housing, and a handle fixed to the plug above said lid.

4. In air brake apparatus, the combination of a cock for the brake or train pipe having a rotatable plug, a cylinder and a piston reciprocable therein, passages connecting one end of the cylinder with the cock at opposite sides of said plug, a rack connected to reciprocate with the piston, a gear member actuated by said rack and connected to said plug, and a housing inclosing said rack and gear member and having a recess forming a guide for said rack.

In testimony whereof I have hereunto set my hand in presence of two subscribing witnesses.

FRANK S. CRAVENS.
